CLAIM

We claim the ornamental design for a container, as shown and described.

DESCRIPTION

FIG. 1 is a front/right/top perspective view of a container according to a first exemplary embodiment;
FIG. 2 is a front/left/bottom perspective view thereof;
FIG. 3 is a front elevational view thereof, for which the rear elevational view would be identical;
FIG. 4 is a right side elevational view thereof, for which the left side elevational view would be identical;
FIG. 5 is a top plan view thereof;
FIG. 6 is a bottom plan view thereof;
FIG. 7 is an exploded front elevational view of the container shown in FIG. 1 with the lid removed from the body of the container, for which the rear elevational view would be identical;
FIG. 8 is a top plan view of the container shown in FIG. 1 with the lid removed;

FIG. 9 is a front/right/top perspective view of a container according to a second exemplary embodiment;

FIG. 10 is a front/left/bottom perspective view thereof;

FIG. 11 is a front elevational view thereof, for which the rear elevational view would be identical;

FIG. 12 is a right side elevational view thereof, for which the left side elevational view would be identical;

FIG. 13 is a top plan view thereof;

FIG. 14 is a bottom plan view thereof;

FIG. 15 is an exploded front elevational view of the container shown in FIG. 9 with the lid removed from the body of the container, for which the rear elevational view would be identical; and,

FIG. 16 is a top plan view of the container shown in FIG. 9 with the lid removed.

The broken line showing of the food container represents unclaimed subject matter and forms no part of the claimed design. The dash-dot-dash lines immediately adjacent the shaded areas represent the bounds of the claimed design.
